POURING LID FOR CANS

Christy M. Del Mas, New York, N. Y., assignor to Michael P. Grace, New York, N. Y.

Application May 6, 1953, Serial No. 24,872

Term of patent 14 years

(Cl. D58—26)

Figure 1 is a side perspective view of a pouring lid for cans, embodying my new design, and

I claim:

The ornamental design for a pouring lid for cans, as shown.
